EUGÈNE SCHNEIDER, OF PARIS, FRANCE, ASSIGNOR TO SCHNEIDER & CIE, OF PARIS, FRANCE, A LIMITED JOINT-STOCK COMPANY OF FRANCE.

SAFETY MECHANISM FOR USE WITH GUN BREECH-BLOCKS COMPRISING REMOVABLE FIRING-TUBE HOLDERS.

1,336,096.

Specification of Letters Patent.

Patented Apr. 6, 1920.

Original application filed August 21, 1918, Serial No. 250,869. Divided and this application filed October 27, 1919. Serial No. 333,678.

To all whom it may concern:

Be it known that I, EUGÈNE SCHNEIDER, a citizen of the Republic of France, and a resident of Paris, France, have invented new and useful Improvements in Safety Mechanism for Use with Gun Breech-Blocks Comprising Removable Firing-Tube Holders, which invention is fully set forth in the following specification.

10 This invention relates to breech mechanism for guns, and it has for its object to provide an improved safety apparatus which will prevent any operation of the firing mechanism, in guns provided with 15 screw-threaded breech-blocks having a removable firing-tube holder, so long as the breech is open or only partially closed.

More specifically, it relates to certain mechanical expressions of the generic invention 20 disclosed and claimed in my application Serial No. 250,869, filed August 21, 1918, of which this application is a division.

The improved safety apparatus, which is necessary for preventing premature firing 25 due to the inertia of the firing pin when closing the breech, consists first in a device for preventing the insertion of the firing-tube holder so long as the breech is only partially closed, and second in a device for 30 preventing the firing hammer from coming into operation so long as the firing-tube holder is only partially inserted in the recess provided for it in the breech-block. The improved safety apparatus thus renders it necessary first that the breech shall be completely closed before the firing-tube holder can be engaged in its recess, and second that the firing-tube holder shall be completely 35 inserted in its recess in the breech-block 40 before the firing hammer can engage the firing pin.

The safety device for preventing the firing-tube holder from being inserted in position so long as the breech is only partially closed is shown as consisting of a bolt 45 movably located in the breech-block holder and having one end which is caused to project by the breech-block in such a manner as to prevent the insertion of the firing-tube holder so long as the inner end of the said bolt has not been brought opposite a recess, formed in the breech-block, by the complete

movement of the breech-block screw into the breech-nut.

The safety device for preventing the operation of the firing hammer so long as the firing-tube holder is only partially inserted in its recess is shown as consisting of a notch formed in the front face of the firing-tube holder to which there corresponds a projection on the hammer whereby the notch in the one part will register with the projection on the other part only after the complete insertion of the firing-tube holder into its recess, which registration is necessary before 65 the head of the hammer can come in contact with the firing pin.

The invention is capable of receiving a variety of mechanical expressions, two of which are shown on the accompanying drawings, but it is to be expressly understood that the drawings are for purposes of illustration only, and are not to be construed as a definition of the limits of the invention, reference being had to the appended claims 75 for that purpose.

In the drawings:

Figure 1 is an end elevation, partly in section, of breech mechanism comprising a known type of breech and breech-block, and 80 illustrating one embodiment of this invention;

Fig. 2 is a vertical axial section showing the breech closed and the parts in firing position;

Fig. 3 is a corresponding section showing the breech only partially closed and the safety apparatus in operative position;

Fig. 4 is a fragmentary vertical section through another embodiment of this invention;

Fig. 5 is a vertical axial section showing the breech closed and the parts in firing position; and

Fig. 6 is a corresponding section showing the breech only partially closed and the safety apparatus in operative position.

Referring to Fig. 1, the breech mechanism illustrated comprises a breech-block A having the usual screw-threaded sectors separated by plain sectors. To the screw-threaded and plain sectors on the breech-block, there correspond respectively screw-threaded sectors b^1 and plain sectors b^2 of the screw-

thread of the breech-nut B. The breech-block A is permanently connected to a breech-block holder C that is hinged to the nut B by a pin, and the breech-block is adapted to turn in its holder to enable it to be screwed into and out of the breech-nut.

The breech-block is operated by means of a lever E which, owing to the interposed stud e, imparts longitudinal motion to the rack F which is guided in the holder C. This rack engages, by means of its teeth f, a toothed sector a² formed on the breech-block. By this means, movements imparted to the breech-block by the lever E effect the screwing or unscrewing of the breech-block screw into and out of the breech-nut. When unscrewed, the whole system consisting of the lever E, the holder C, the rack F and the breech-block A, may be rotated to withdraw 20 the breech-block from the breech.

In the form shown in Figs. 1 to 3, G is the removable firing-tube holder which may be of any suitable construction. In the embodiments shown, it is assumed that the firing-tube holder G, together with its contained firing tube H, is formed, for the purpose of inserting and withdrawing the same into and out of the breech-block, with a screw-thread g working in an internal 30 screw-thread c formed in the holder C.

The improved safety apparatus of the present invention comprises first a bolt I movable in a recess formed in the holder C¹. The bolt I is fixed to a guide sleeve I¹ movable in a recess C, also formed in the breech-block holder C, and under the action of a spring I² that tends to force said bolt outward. The outward movement of the bolt is limited by a projection C⁴, carried 40 by the breech-block holder, which engages in a slot i² in the sleeve.

When the breech-block has been screwed home in the breech-nut, there is presented opposite the head of the bolt I a notch a³, into which the head of the bolt i may move.

So long as the breech is only partially closed, the bolt I, not being opposite the notch a³ will occupy the position shown in Fig. 3. Therefore, the firing-tube holder G, provided with a collar G¹, can not be screwed into its recess because the said collar strikes against the arm that connects the bolt I to its guide sleeve I¹. As soon, however, as, owing to the complete closure of the breech, the bolt I is in front of the notch a³, it is possible to screw-in the firing-tube holder. During this movement, the pressure exerted by the collar G¹ causes the bolt to enter its recess and the bolt comes then 60 into the position shown in Fig. 2.

When on the one hand the breech is completely closed, and on the other hand the firing-tube holder G is screwed home into the breech-block holder, the front face of 65 the firing-tube holder G then presents, in

the path of the firing hammer J, a notch g¹ into which a projection j on said hammer can enter.

In order to open the breech, it is first necessary to withdraw the firing-tube holder G. This previous withdrawal, which is obligatory by reason of the obstacle opposed by the bolt I to any unscrewing of the breech-block from the breech-nut, constitutes also to a certain extent a safety device 75 against hanging fire. As a matter of fact, since the breech remains necessarily closed during the time required for the withdrawal of the firing-tube holder, hanging fire may in most cases occur without danger to the gun crew. Moreover, when the firing-tube holder has been withdrawn, a hanging fire gives rise through the uncovered aperture of the vent passage to a jet of smoke which will warn the gun crew that they must deter 80 the opening of the breech.

When the firing-tube holder G—H has been withdrawn, the retraction of the bolt I, by the spring I², makes possible the unscrewing of the breech-block. Thereafter, 90 so long as the notch a³ has not been brought opposite the inner end of the bolt, the unnotched portion of the breech-block maintains the said bolt in the position which it occupies in Fig. 3 and the bolt constitutes 95 an obstacle to the engagement of the firing-tube holder G in the breech-block holder C. In order to enable a firing-tube holder charged with a fresh firing tube to be inserted in position, it is therefore absolutely 100 necessary that the breech-block be first screwed home into the breech-nut. On the other hand, the complete insertion of the firing-tube holder G into its recess in the breech-block holder is absolutely necessary 105 in order to allow the firing hammer J to strike the firing pin K, since, so long as the firing-tube holder G presents opposite the projection j of the hammer any portion of its front face other than the notch g¹, the hammer is prevented from coming into its operative or striking position.

In the form shown in Figs. 4, 5 and 6, the notch a³ is formed in the front face of the breech-block A and the bolt proper I consists of a projection on the guide sleeve I¹. The outward movement of the whole system I—I¹ is limited by a plate C⁵ screwed to the breech-block holder C and serving as a stop for the bolt I. A hole is provided in the said plate for the passage of the sleeve I¹.

As in the preceding example, a previous withdrawal of the firing-tube holder is necessary in order to allow of opening the breech.

While the embodiments illustrated on the drawings have been described with considerable particularity, it is to be understood that the invention is not to be restricted thereto, as the same is capable of receiving a variety 130

of mechanical expressions some of which will readily suggest themselves to those skilled in the art, while certain parts thereof are capable of use without other parts 5 thereof. Reference is therefore to be had to the appended claims for a definition of the limits of the invention.

What is claimed is:

1. In combination with a breech-block, 10 its holder and a firing-tube holder adapted to be positioned in a recess in the breech-block holder, means to prevent insertion of the firing-tube holder into its recess until the breech-block is moved into its closed position, said means comprising a horizontally- 15 movable bolt adapted to project into the path of the firing-tube holder when the breech-block is not in its closed position.

2. In combination with a breech-block, 20 its holder and a firing-tube holder adapted to be positioned in a recess in the breech-block holder, means to prevent insertion of the firing-tube holder into its recess until the breech-block is moved into its closed position, 25 said means comprising a spring-operated bolt adapted to be projected into the path of the firing-tube holder, and means whereby said bolt may be withdrawn when the breech-block is moved into its closed position.

3. In combination with a breech-block, 30 its holder and a firing-tube holder adapted to be positioned in a recess in the breech-block holder, means to prevent insertion of the firing-tube holder into its recess until the breech-block is moved into its closed position, said means comprising a spring-operated bolt adapted to project into the path of the firing-tube holder, a recess in the breech-block adapted to register with said bolt when the breech-block is in its closed position, and means for moving said bolt into said last-named recess.

4. In combination with a breech block, 40 its holder and a firing-tube holder adapted to be positioned in a recess in the breech-block holder, means to prevent insertion of the firing-tube holder into its recess until the breech-block is moved into its closed position, 45 said means comprising a horizontally-movable bolt adapted to project into the path of the firing-tube holder, a recess in the breech-block adapted to register with said bolt when the breech-block is in its closed position, and an element on the firing-tube holder adapted to engage said bolt in said last-named recess.

5. In combination with a breech-block, 50 its holder and a firing-tube holder adapted to be positioned in a recess in the breech-block holder, means to prevent insertion of the firing-tube holder into its recess until the breech-block is moved into its closed position, 55 said means comprising a bolt adapted to project into the path of the firing-tube

holder, a recess in the breech-block adapted to register with said bolt when the breech-block is in its closed position, and a spring adapted to move said bolt into the path of the firing-tube holder upon withdrawal of 60 the latter.

6. In combination with a breech-block, 65 its holder and a firing-tube holder adapted to be positioned in a recess in the breech-block holder, means to prevent insertion of the 70 firing-tube holder into its recess until the breech-block is moved into its closed position, said means comprising a horizontally- 75 movable bolt, a recess in the breech-block, and means on the firing-tube holder for en- 80 gaging said bolt in said last-named recess when the breech-block is in closed position.

7. In combination with a breech-block, 85 its holder and a firing-tube holder adapted to be positioned in a recess in the breech-block holder, means to prevent insertion of the 90 firing-tube holder into its recess until the breech-block is moved into its closed position, said means comprising a horizontally- 95 movable bolt, a guide sleeve for said bolt, a recess in the breech-block, a spring coacting with said sleeve and normally maintaining said bolt disengaged from said last-named recess, and means on the firing-tube 100 holder for engaging said bolt with said last-named recess when the breech-block is in closed position.

8. In combination with a breech-block, 105 its holder and a firing-tube holder adapted to be positioned in a recess in the breech-block holder, means to prevent insertion of the 110 firing-tube holder into its recess until the breech-block is moved into its closed position, said means comprising a horizontally- 115 movable bolt, a recess in the breech-block, a spring normally maintaining said bolt disengaged from said last-named recess, and means on the firing-tube holder for engaging said bolt with said last-named recess when the breech-block is in closed position.

9. In combination with a breech-block, 120 its holder, a firing-tube holder adapted to be positioned in a recess in said breech-block holder, and a firing hammer, means to prevent insertion of said firing-tube holder into said recess until the breech-block is moved into its closed position and comprising a spring-operated bolt movable into the path of said firing-tube holder, and means to prevent the operation of said firing hammer prior to the complete insertion of said firing-tube holder into its recess.

10. In combination with a breech-block, 125 its holder, a firing-tube holder adapted to be positioned in a recess in said breech-block holder, and a firing hammer, means to prevent insertion of said firing-tube holder into said recess until the breech-block is moved into its closed position and comprising a 130

horizontally-movable bolt movable into the path of said firing-tube holder, and means to prevent the operation of said firing hammer prior to the complete insertion of said firing-tube holder into its recess.

11. In combination with a breech-block, its holder, a firing-tube holder adapted to be positioned in a recess in the breech-block holder, and a firing hammer, means to prevent insertion of said firing-tube holder into said recess until the breech-block is moved into its closed position and comprising a

spring-operated bolt movable into the path of said firing-tube holder, and means to prevent the operation of said firing hammer prior to the complete insertion of said firing-tube holder into its recess, said last-named means comprising a recess in one of said elements adapted to register with means on the other of said elements when said firing-tube holder is in operative position.

In testimony whereof I have signed this specification.

EUGENE SCHNEIDER.
